(57) **CLAIM**

The ornamental design for a body buffer, as shown and described.

DESCRIPTION

FIG. 1 is a right side, top, rear perspective view of a first embodiment of a body buffer showing our new design; FIG. 2 is a front elevation view of the body buffer of FIG. 1;

FIG. 3 is a rear elevation view of the body buffer of FIG. 1; FIG. 4 is a left side elevation view of the body buffer of FIG. 1;

FIG. 5 is a right side elevation view of the body buffer of FIG. 1;

FIG. 6 is a top plan view of the body buffer of FIG. 1; FIG. 7 is a bottom plan view of the body buffer of FIG. 1; FIG. 8 is a left side, front, bottom perspective view of the body buffer of FIG. 1;

FIG. 9 is a right side, top, rear perspective view of a body buffer showing a second embodiment of our new design; FIG. 10 is a front elevation view of the body buffer of FIG. 9;

FIG. 11 is a rear elevation view of the body buffer of FIG. 9;

FIG. 12 is a left side elevation view of the body buffer of FIG. 9;

FIG. 13 is a right side elevation view of the body buffer of FIG. 9;

FIG. 14 is a top plan view of the body buffer of FIG. 9; FIG. 15 is a bottom plan view of the body buffer of FIG. 9; and,

FIG. 16 is a left side, front, bottom perspective view of the body buffer of FIG. 9.

The broken lines showing portions of the design in FIGS. 9-16 are included for the purpose of illustrating environment and unclaimed features and form no part of the claimed design.

1 Claim, 12 Drawing Sheets
